UNITED STATES PATENT OFFICE.

DAVID CLARENCE SHERMAN, OF POULTNEY, VERMONT.

GUARD FOR SLATE-TRIMMING MACHINES.

1,235,063.

Specification of Letters Patent. Patented July 31, 1917.

Application filed September 9, 1916. Serial No. 119,203.

To all whom it may concern:

Be it known that I, DAVID CLARENCE SHERMAN, a citizen of the United States, residing at Poultney, in the county of Rutland, State of Vermont, have invented certain new and useful Improvements in Guards for Slate-Trimming Machines, of which the following is a description, reference being had to the accompanying drawings, forming a part thereof.

My invention relates to guards for slate trimming or other machines in which a rotary or otherwise movable knife is used to cut or break the material operated on and is designed to protect the operator of such a machine from injury from the movable knife.

In slate trimming machines of the type for which my invention is particularly intended the slate to be trimmed rests upon a stationary knife with which a rotary or swinging knife coöperates to cut or break the slate along the line of the edge of the stationary knife. In order to effect this cutting or breaking of the slate the rotary or swinging knife must not only be of considerable weight but must be brought down upon the slate with very considerable force. The slate is held in position by the hands of the operator and the operation of the movable knife is usually controlled by or actuated by a treadle. There is always more or less danger that the operator's foot may slip on the treadle and in putting out his hand to catch himself the hand may get between the knives and be injured.

It is the object of my invention to provide a simple and inexpensive and at the same time effective guard by which without interfering with the operation of the machine it will be made impossible for the operator to accidentally get his hand between the knives.

With this and other objects hereinafter explained in view my invention consists in the construction and combination of elements hereinafter described and particularly pointed out in the claims.

Referring to the drawings. Figure 1 is a front elevation of a slate trimming machine provided with the guard of my invention.

Fig. 2 is an end view taken from the right of Fig. 1.

Fig. 3 is a vertical sectional view on the 55 line 3—3 of Fig. 1 and

Fig. 4 is a top plan view of the machine shown in Figs. 1, 2 and 3 with the guard removed.

In the drawings 1 indicates the frame of 60 the slate trimming machine having front top plate 2 and rear top plate 3. Between these front and rear top plates are arranged bearings 4 and 5 for shaft 6 these bearings being arranged to be adjustable by set 65 screws 7 in the front plate 2 and set screws 8 in the rear plate 4. To the inner face of the front plate 2 is bolted the stationary knife 9. The movable knife 10 is carried by arms 11 and 12 on shaft 6. The movable 70 knife is so constructed that its cutting edge is not parallel with the axis of shaft 6 but is so curved that its end which is at the right in Fig. 1 comes first into line with the edge of the stationary knife.

On one end of shaft 6 is a fly wheel 13 having crank pin 14 connected by pitman 15 with treadle 16.

A gage bar 17 is pivoted at 18 to a fixed plate 19 carried by the front plate 2 the 80 gage bar being adjustable on its pivot 18 by means of slot 20 and bolt 21. The gage bar 17 is provided with notched gage 22 which is adjustable on the gage bar by means of slots 23 and bolts 24.

In the operation of the machine the slate to be trimmed is laid with its front end on the stationary knife and its left hand edge against the gage bar. The treadle is then pressed to rotate the shaft bringing the 90 rotary knife down on the end of the slate shearing off the portion projecting beyond the edge of the stationary knife. The slate having one edge thus trimmed is then turned to bring the trimmed edge against 95 the gage bar and the machine again operated. By turning the slate all four edges may be trimmed. By means of the gage bar adjoining edges may be trimmed to right angles and by means of the notches 100 on the gage bar the slate may be trimmed to the size desired.

In the operation of the machine as above described there is always danger that the hand of the operator may get between the 105 knives after the shaft has begun to rotate and as it is necessarily quite heavy it moves with considerable momentum and once

started cannot be stopped quickly and will cut or severely bruise the hand if it is in the path of the rotary knife. In order to make it impossible for such an accident to happen I provide the guard which is the subject of my invention. This comprises end curved bars 20, and 21 and intermediate curved bar 22 connected together along their front ends by horizontal bar 23 and also connected in the rear by horizontal bar 24. The end curved bars 20 and 21 are secured at their rear ends to the top plate 3, preferably as shown by a hinge connection 25. To the front ends of curved bar are secured supports 26 and 27 which are suitably bent to be out of the way of the operating parts of the machine and are bolted to the ends of the frame of the machine by bolts 28, the support 27 being preferably twisted between its ends for convenience in securing its ends respectively to the end curved bar 21 and to the side of the frame of the machine. The intermediate curved bar is secured at its rear end to horizontal bar 24. Secured to the under side of the curved bars 20, 21 and 22 and to the horizontal bars 24 and 25 is a wire netting 29.

The curved bars 20, 21 and 22 are of such length that the front horizontal bar 23 is held a sufficient distance above the plane of the edge of the stationary knife to permit the slate to be trimmed to be inserted and the support 27 is so bent as not to prevent the insertion of the full width of the machine or even wider.

The curved and horizontal bars are preferably formed of flat strips of steel or other metal and the netting is formed of wire sufficiently strong to resist any pressure of the hand of the operator. The curve on which the curved bars 20 and 21 and 22 are formed is approximately an arc of a circle of which the axis of the shaft 6 is the center.

A suitable apron 30 extends from the top front 2 downward and rearward so that the chips from the trimming operation are discharged to the rear.

The guard not only prevents the hands of

the operator from getting between the knives but also prevents chips from flying as the slate is trimmed.

While the guard has been described as applied to a slate trimming machine, it is obvious that it may be applied to any machine in which a rotary knife is arranged to cut or trim sheets or other material in coöperation with a stationary knife.

Having thus described my invention what I claim is:

1. In a cutting machine having a stationary knife and a rotary knife arranged to coöperate with the stationary knife, a guard comprising curved bars secured at their rear ends to the frame of the machine and extending over the knives, a horizontal bar secured to the front ends of the curved bars above the plane of the stationary knife, and a netting carried by the curved arms extending over the rotary knife.

2. In a cutting machine having a stationary knife and a rotary knife arranged to coöperate with the stationary knife, a guard comprising curved bars secured at their rear ends to the frame of the machine and extending over the knives, a horizontal bar secured to the front ends of the curved bars above the plane of the stationary knife, and a netting carried by the curved arms extending over the rotary knife, and supports for the front ends of the curved bars.

3. In a cutting machine having a stationary knife and a rotary knife arranged to coöperate with the stationary knife, a guard comprising curved bars secured at their rear ends to the frame of the machine and extending over the knives, a horizontal bar secured to the front ends of the curved bars above the plane of the stationary knife, and a netting carried by the curved arms extending over the rotary knife, and supports for the front ends of the curved bars, one of said supports being so bent as to leave the full width of the knives unobstructed.

This specification signed this twenty-sixth day of August A. D. 1916.

D. CLARENCE SHERMAN.
